C. E. BRADSHAW

KEY HOLDER

Filed July 2, 1923

Inventor
Charles E. Bradshaw
by Seymour Pearce
Attest

UNITED STATES PATENT OFFICE.

CHARLES E. BRADSHAW, OF WATERBURY, CONNECTICUT.

KEY HOLDER.

Application filed July 2, 1923. Serial No. 648,963.

To all whom it may concern:

Be it known that I, CHARLES E. BRADSHAW, a citizen of the United States, residing at Waterbury, in the county of New Haven and State of Connecticut, have invented a new and useful Improvement in Key Holders; and I do hereby declare the following, when taken in connection with the accompanying drawings and the characters of reference marked thereon, to be a full, clear, and exact description of the same, and which said drawings constitute part of this application, and represent in—

Fig. 1 a face view of a key holder constructed in accordance with my invention, shown in the closed position.

Fig. 2 a plan view with the folder in the open position.

Fig. 3 a sectional view on the line 3—3 of Fig. 2.

Fig. 4 a rear view of the plate detached.

Fig. 5 a plan view of the key-loop detached.

This invention relates to improvement in key holders and particularly to key holders which are purse-like in character, that is, in which the keys are suspended and enclosed by a casing of leather or other suitable material. In the more general construction of key holders, a separate device is provided for each key. The object of this invention is a simple construction which permits a number of keys to be suspended, with means for easily engaging or disengaging the keys, and the invention consists in the construction as hereinafter described and particularly recited in the claims.

In carrying out my invention, I employ a plate 10, one edge of which is rolled at opposite sides to form sockets 11 and 12, between which there is a lip 13 divided from the sockets by inclined slots 14 leading to notches 15 at the inner ends of the sockets. A key-loop 16 is formed from a single piece of wire having its ends bent into loop-form, with arms 17 and outwardly-extending fingers 18. The plate 10 is riveted, or otherwise secured, to a sheet 19 of leather or other suitable material, provided with a

centrally-arranged bottom-flap 20 and side-flaps 21 and 22.

The key-loop is connected with the plate by contracting the ends 17 and inserting them between the sheet 19 and the lip 13, so that the fingers 18 will be in line with the sockets 11 and 12, into which they will enter when released. When thus entered, the loop is turned downward, so that the ends of the arms enter the notches 15, whereby the loop is held in its closed position. The keys are placed upon the loop in the usual manner, and the flap 20 folded up over the lower ends and then the flaps 21 and 22 are turned inward and connected by a socket 23 and stud 24 of an ordinary snap-fastening. The loop may be turned upward for convenience in using the keys, but cannot be disengaged from the plate until the ends have been contracted so as to withdraw the fingers from the sockets. When in the "down" position, the ends of the arms entering the sockets 15 will lock the loop in place.

I claim:

1. A key holder comprising a folder, a plate secured thereto, said plate formed with sockets and with a centrally-arranged lip and a key-loop formed from a single piece of wire and provided at its ends with fingers adapted to enter said sockets.

2. A key holder comprising a folder, a plate secured thereto, said plate formed with two inwardly-opening sockets and with a centrally-arranged lip and also with grooves between the ends of the sockets and lip, and a key-loop having arms and outwardly-extending fingers, said fingers adapted to enter the said sockets, whereby the loop is hinged to the plate, said sockets also formed at their inner ends with notches into which the arms of the loop extend.

In testimony whereof, I have signed this specification in the presence of two subscribing witnesses.

CHARLES E. BRADSHAW.

Witnesses:

FREDERIC C. EARLE,
MALCOLM P. NICHOLS.
